ATTORNEY.

UNITED STATES PATENT OFFICE

2,236,253

LEAKPROOF VALVE

John B. Testori, Detroit, Mich.

Application January 18, 1940, Serial No. 314,400

1 Claim. (Cl. 251—24)

It is a well known fact that valves are among the most important elements of industry in general, and it is also known that every type of known valve today will leak more or less, and which has caused a great deal of difficulty.

One of the objects of this invention is to produce a valve construction that is entirely new and that is positively leak-proof.

Another advantage of the invention is the fact that there are no moving parts which are subject to wear and causing them to leak.

While the invention is primarily designed so as to accommodate beer lines, it is no less advantageous as applied for water and other liquids, 15 or for air.

With the foregoing in mind, it will become readily apparent that the invention possesses further advantages, all of which will be clearly revealed during the course of the following detailed description, illustrated throughout the accompanying drawing, and more fully pointed out in the appended claim.

With reference to the drawing:

Figure 1 is a top plan view of the complete invention; and Figure 2 is a side elevation thereof.

Figure 3 is an enlarged sectional assembly taken through the longitudinal center thereof.

Figure 4 is a top plan view of the bowl element of the device; and Figure 5 is a side elevation thereof.

Figure 6 is a side elevation of the stem member.

Figure 7 is a top plan view of the cap member; and Figure 8 is a side elevation thereof.

Figure 9 is a top plan view of the disc member; and Figure 10 is a side elevation thereof.

Figure 11 is a top plan view of the diaphragm; and Figure 12 is a side elevation thereof.

The invention comprises a body that is composed of a suitable metal and having bowl 1. A portion of one end of bowl 1 is extended tubular portion 2 which is adapted to connect to a beer barrel, and the opposite portion is extended and forming inclosed end 3 as shown.

Tubular portion 4 is depended downwardly from bowl 1 and is adapted to threadedly engage a pipe line to the beer coils.

With particular reference to Figure 3 the complete valve construction is indicated as in an open position.

Cap 5 is provided and is adapted to threadedly engage bowl 1, and it is seen that a portion of said cap is extended upwardly and forming thereby hexagon nut 6, and in the center of the cap is threaded opening 7 so as to similarly engage

stem 8, and said stem having hand-hold 9 where shown.

Still referring to Figure 3, it is seen that floating disc 10 is provided and has flanged edge 11 as shown, also similar flanged portion 12 upon 5 the inside of cap 5. The purpose of portions 11 and 12 is to prevent disc 10 from falling out of cap 5 when the same is removed from bowl 1.

Bowl 1 is provided with inner seat 13 so as to accommodate flexible rubber washer 14 and metal 10 diaphragm 15 as shown.

The purpose of disc 10 is to prevent wear upon diaphragm 15, as when stem 8 is pressed upon said disc, the disc firmly presses the diaphragm. In this manner frictional wear between these elements is eliminated.

Tubular portion 4 is provided with circumferential raised flange 16 at the upper end thereof, providing an enlarged beer collecting chamber around the upper end of the outlet port 4, and 20 the valve is closed by threadedly lowering stem 8 upon disc 10 thus forcing diaphragm 15 downwardly upon flange 16 and in this manner passage between tubular portions 2 and 4 is closed. The valve is likewise opened by threadedly back- 25 ing stem 8 thus releasing pressure upon disc 10 and diaphragm 15.

The diaphragm 15 is held seated only against the top of the outlet port 4 so that the beer flowing into the chamber under low pressure will 30 accumulate in the chamber and present sufficient pressure, even though low, against the bottom face of the diaphragm to cause the latter to positively and uniformly move upward to unseat the outlet port when the threaded stem 8 is 35 moved upwardly and disengaged from the upper face of the floating disc.

As previously stated, the principle of this invention is well adapted for use as an air valve, or for water and other liquids.

In conclusion, let it be understood that the complete disclosure herewith is merely illustrative of the general principle of the invention sought to be protected by Letters Patent, and that any contemplated change made therein would 45 fall directly within the scope of the claim.

Having thus fully described my invention, what I claim as new is:

In a valve structure, a body including an enlarged bowl, an inlet port leading into the bottom 50 of the bowl at one side thereof, a centrally disposed outlet port extending downwardly from the bottom of the bowl, the upper end of the outlet port projecting above the bottom of the bowl, a diaphragm arranged in the bowl, a cap member 55

5 detachably secured in the upper portion of the bowl, the bottom face of the cap member having a pocket formed therein, a flanged disc loosely mounted for vertical movement in said pocket, means at the outer face of the pocket to prevent disengagement of the disc from the pocket, the bottom face of the disc contacting the upper

face of the diaphragm, and a stem threaded through the top of the cap member and extending into the pocket for engagement with the upper face of the disc to force the central portion of the diaphragm into sealing engagement with the projected upper end of the outlet port.

JOHN B. TESTORI.
